DAVID SCHANE, OF NEW YORK, N. Y.

SUPPORTING MEANS FOR SUBMARINE MINES.

1,150,889.

Specification of Letters Patent. Patented Aug. 24, 1915.

Application filed March 19, 1915. Serial No. 15,483.

To all whom it may concern:

Be it known that I, DAVID SCHANE, a citizen of the United States, residing at New York, in the county of New York and State of New York, have invented certain new and useful Improvements in Supporting Means for Submarine Mines, of which the following is a specification.

This invention relates to improvements in supporting means for submarine mines commonly used for protection of coast defenses or for blockading certain waterways, and it is the particular object of the invention to make such mines or other explosive carrying containers effective for a very great area whereby the efficiency of these weapons is considerably increased and the number of them correspondingly decreased.

Various other objects will appear in the following specification in which a preferred construction of the mine and its moorings is disclosed and in which—

Figure I shows a cross section through a body of water, the mine and supporting means for the same being shown in elevation; Fig. II illustrates a plan view of the arrangement shown in Fig. I; Fig. III shows a plan view of the mine in a position about to contact with a moving vessel; and Fig. IV shows a view similar to Fig. I illustrating a modified construction of the mine supporting means.

All of the above views are shown in diagrammatic form sufficiently illustrative, however, of the principle of my invention.

Like characters of reference denote similar parts throughout the several views and the following specification.

1 is a mine of the type which contains a high explosive, subject to violent discharge when brought in contact with a moving object with sufficient force.

2 is a cable of steel or other suitable material extending upwardly to a float 3.

5 Where fastened to float 3, cable 2 is run in a horizontal direction to connect with float 4 from which cable 2 is suspended downwardly and firmly held in a stationary position by a suitable anchor 5.

6, 7 and 8 are intermediate floats adapted to support the cable 2.

Floats 3, 4, 6, 7 and 8 are preferably of such proportion and buoyancy as to support the cable and the mine a distance sufficiently below the surface of the water so as to render them invisible. This, however, is not

absolutely necessary and may be varied from by adapting float 4 or any other floats, or, if desired, all of them, to be on the level of the water, indicative of the approximate position of the mine. It is also obvious that the use of intermediate floats 6, 7, and 8 may be dispensed with or increased in accordance with the weight of the mine and the length of the cable supporting the same. 60 The construction may further be modified by attaching the mine directly to float 3, if desired. Mine 1 is also held stationary by a suitable anchor 9; this anchor however must be of much lighter weight than anchor 5, 65 and just heavy enough to withstand any current in the water, and may be entirely omitted in still water.

A modification of the mine supporting means is shown in Fig. IV. In this figure 75 mines 1 and 1^a are supported by cable 2 and floats 3 and 3^a, and held stationary in the center by anchor 5 suspended from float 4, intermediate floats 6, 7, 8, and 6^a, 7^a, 8^a supporting the weight of the cable 2 and the 80 mines 1 and 1^a, as explained above with reference to Fig. I. In this manner also a series of mines may be radially or otherwise connected to float 4, insuring obviously a still greater radius of action. Anchors 9 85 and 9^a may further be attached to mines 1 and 1^a respectively, to prevent the shifting of the mines due to currents in the water.

The operation of my mine supporting means and its advantages are as follows: 90 Cable 2 is placed across the passage which it is desired to blockade, firmly anchored at one end and supporting mine 1 at the other. Should a vessel 10 strike cable 2, it would gradually deflect the cable, thereby drawing the mine 1 closer to itself, as shown in Fig. III, until finally mine 1 will contact with the sides of the vessel 10 when the explosion will occur.

Heretofore, mines were generally placed 100 in the water, anchored at from 100 to 500 feet apart, to prevent the explosion of one damaging the other. They were usually arranged in two or more lines, the mines of one line covering the spaces left between the 105 mines of the next. There was therefore always the possibility of a ship passing through a line of mines without coming within the destructive area of any. It is obvious that, with my improved arrangement of supporting and anchoring the mine, the usefulness 110 of the same and its effective range is greatly

increased, while a considerable smaller quantity of mines can be employed to maintain a complete blockade, making it absolutely impossible for any vessel to pass through a strait so protected, without striking a cable and subsequently exploding the attached mine.

While I have shown for purposes of illustrating and have described only a few embodiments of my invention, it is to be understood that the same is susceptible of various other modifications from details herein shown and described without departing from the spirit thereof.

What I claim as new is:

1. A floating cable, an anchor suspended from one end of the said cable, a submarine mine suspended from the other end of said cable, and current resisting means, of less resistance than the said anchor, fastened to the said mine.

2. A submerged cable supported by suitable floats positioned below the surface of the water, an anchor suspended from one end of the said cable, and a submarine mine suspended from the other end of the said cable, a second anchor fastened to the said mine, the said second anchor being of considerably less weight than the said first mentioned anchor.

3. A cable supported by suitable floats below the surface of the water, an anchor suspended from one end of the said cable, and a submarine mine suspended from the other

end of the said cable, and current resisting means of less resistance than the said anchor fastened to the said mine.

4. The combination of a submarine mine, a submerged floating cable extending in a lateral direction connected to the said mine, means holding one end of the said cable in a stationary position, and current resisting means, of less resistance than the said cable holding means, connected to the said mine.

5. The combination of a float, an anchor suspended from the said float, a series of cables extending radially away from the said float, other floats supporting the said cables in the water, mines of the character described suspended from the outer ends of the said cables and current resisting means, of less resistance than the said anchor, fastened to the said mines.

6. A cable supported by a series of floats, an anchor suspended from a point intermediate the ends of the said cable, mines of the character described suspended from both ends of the said cable, and other anchors, of considerably less weight than the said first mentioned anchor, fastened to the said mines.

In testimony whereof I have hereunto set my hand in presence of two subscribing witnesses.

DAVID SCHANE.
